FEED-WATER HEATER

Joseph F. Sebald, Arlington, N. J., assignor to
 Worthington Pump and Machinery Corporation,
 Harrison, N. J., a corporation of Delaware

Application August 31, 1940, Serial No. 354,975

14 Claims. (Cl. 261—111)

This invention relates to improvements in apparatus for heating and degasifying liquids, and more particularly to an improved apparatus for heating and deaerating water for boiler feed service and other services or purposes requiring practically oxygen free water.

An object of the present invention is the provision of an improved apparatus for providing a high degree of heating and degasification wherein the apparatus employed, while giving a very high degree of heating and degasification, will compare favorably with heaters of comparable capacity, of other approved types, as to size, weight and cost of manufacture.

The present invention embodies the same new and advantageous feature of intimate mixing of the steam and water to provide improved heating and degasifying of the water as is set forth in my companion application, Serial No. 354,974, and differs from the method and apparatus set forth in that application fundamentally in the steps or cycle of heating the water; reboiling or flashing for initial degasification; second stage heating of the water by intimate mixing of the steam and water; and final reboiling or flashing for final degasification of the water.

With these and other objects in view, as may appear from the accompanying specification, the invention consists of various features of construction and combination of parts, which will be first described in connection with the accompanying drawings, showing a feed water heater of the preferred form embodying the invention, and the features forming the invention will be specifically pointed out in the claims.

In the drawings:

Figure 1 is a longitudinal section through a feed water heating apparatus constructed in accordance with the present invention.

Figure 2 is a horizontal section on the line 2—2 of Figure 1.

Figure 3 is a horizontal section on the line 3—3 of Figure 1.

Referring more particularly to the drawings, the improved feed water heating apparatus comprises a shell 1, which has a cylindrical partition 2 therein spaced from the inner surface of the shell 1. A dome-like partition 3 is mounted within the enclosure formed by the circular partition 2 and forms an initial heating chamber 4, into which the water to be treated is sprayed in a finely divided form by a plurality of spray valves 5, of any approved type commonly used in open type deaerating feed water heating apparatus.

The water to be treated passes to the spray valves 5 through a suitable inlet 6.

The dome-like partition 2 has its lower edge extending into a trough-like structure 7 which, cooperating with the dome-like partition, forms a water seal between the initial heating compartment 4 and the initial deaerating compartment 9. The water passes through the water seal 7 and over the upper edge of the circular wall 10 of the water seal into the compartment 9. It then passes downwardly in this compartment 9 to the lower water collection portion 11 thereof, from which it passes through the outlet 12 into a mixing passage 14 formed by the member 15 and the lower inclined portions of the partition 2 which form the water collection space 11.

The steam first enters the feed water heating apparatus through the inlet pipe 16, which extends axially through the water collection space 11 and opens out at its lower end into the mixing space 14. The lower, outer end of the steam inlet member or pipe 16 is curved upwardly and outwardly, as shown at 17, so that water passing through the opening 12 will be guided into the space 14 in a direction parallel to the passage of the steam, upwardly through the mixing space 14. The steam and water will thoroughly and intimately mix in the mixing space 14 providing a high degree of heating of the water. As clearly shown in Figure 1 of the drawings, the space 14 gradually increases in cross-sectional area from the point of entrance of the steam and water through to its outlet end 18, resulting in a lowering of the pressure during travel of the mixed steam and water through the passage 14. The mixed steam and water are projected from the outlet 18 into the interior of the shell 1 at a point where the pressure is lower than the pressure in the mixing passage. This results in a reboiling or flashing of part of the water and complete separation of the water, oxygen and non-condensable gases, together with the non-condensed steam. A splash plate 20 may be provided, spaced properly from the outlet 18 so as to prevent the water from splashing into the annular passage 21 within the shell and about the outer surface of the partition 2. This stage, just described, is the final stage of heating and deaeration of the water, and the water falls from the space into which it is projected from the passage 14 into the storage space 22 of the heater. The non-condensed steam and separated oxygen and gases pass upwardly into the passage 21 and through the opening 23 in the top of the partition 2 into the initial heating chamber 4.

where they contact the water being sprayed into the compartment 4, entering the compartment in a path transversally of the path of flow of the water. This provides the initial heating step in the cycle of heating and degasifying the water to be treated. The partially heated water, together with non-condensed steam and gases, passes through the water seal 7, providing a short, thorough mixing passage where the water and the steam will intimately mix and pass out through the water seal into the initial or first deaeration chamber 8. This chamber 8 will be at a lower pressure than the pressure maintained in the water seal 7, with the result that a part of the water will reboil or flash in the chamber 8, providing the initial or first step or stage of deaeration of the water. The gas separated from the water in this initial stage compartment, together with the gases which were released by the final deaeration step or stage occasioned by the projection of the water and steam from the mixing passage 14, together with any non-condensed steam, are drawn out from the compartment 8 through a vent connection 25, which is preferably connected to a vent condenser (not shown). The water then passes on through the collection space 11 to the mixing passage 14 for final heating and for projection into the interior of the casing 1 for final deaeration.

Thus, in the present type of feed water heating apparatus, the cycle of operation is initial heating, as the first step; deaeration, as the second step; mixing and final heating, as the third step; and final deaeration, as the fourth step, with the return of the non-condensed steam and separated gases to the initial deaeration chamber, from which they are drawn off.

A spring loaded check valve 26 is shown as mounted in the mouth or outlet of the steam inlet pipe 18. This check valve serves to prevent a back flow of water through the steam inlet at such times as there is no flow of steam, or when the flow of steam is of such nature as to permit the back flow of water. This check valve may be of any approved type, and need not necessarily be mounted in the outlet of the steam inlet pipe, but may be placed at any convenient location in the pipe.

It will be understood that the invention is not to be limited to the specific construction or arrangement of parts shown, but that they may be widely modified within the invention defined by the claims.

What is claimed is:

1. Water heating and deaerating apparatus comprising in combination, a shell, means in the shell forming an initial heating chamber, means for passing water into said chamber, a water seal at the outlet of said chamber, means in said shell forming a low pressure flashing chamber at the outlet of said initial heating chamber, an inlet for steam, means in said shell forming a confined mixing passage for receiving water from said flashing chamber and steam from said initial inlet, and thoroughly mixing the steam and water during their flow through said passage, said passage discharging into the shell in a low pressure space to provide a second flashing of the water and final deaeration thereof.

2. Water heating and deaerating apparatus comprising in combination, a shell, means in the shell forming an initial heating chamber, means for passing water in a finely divided form into said chamber, a water seal at the outlet of said chamber, means in said shell forming a low pres-

sure flashing chamber at the outlet of said initial heating chamber, an inlet for steam, means in said shell forming a confined mixing passage for receiving water from said flashing chamber and steam from said initial inlet and thoroughly mixing the steam and water during their flow through the passage, said passage discharging into the shell in a low pressure space to provide a second flashing of the water and final deaeration thereof, and means for directing non-condensed steam and released gases from the point of final deaeration into said initial heating chamber.

3. Water heating and deaerating apparatus comprising in combination, a shell, means in the shell forming an initial heating chamber, means for passing water in a finely divided form into said chamber, a water seal at the outlet of said chamber, means in said shell forming a low pressure flashing chamber at the outlet of said initial heating chamber, an inlet for steam, means in said shell forming a confined mixing passage for receiving water from said flashing chamber and steam from said initial inlet and thoroughly mixing the steam and water during their flow through the passage, said passage discharging into the shell in a low pressure space exteriorly of said mixing passage to provide a second flashing of the water and final deaeration thereof, and means for directing non-condensed steam and released gases from the point of final deaeration into said initial heating chamber at a point remote from the water outlet of the initial heating chamber and in a flow direction transversely of the direction of entrance flow of water into the chamber.

4. Water heating and deaerating apparatus comprising in combination, a shell, means in the shell forming an initial heating chamber, means for passing water in a finely divided form into said chamber, a water seal at the outlet of said chamber, means in said shell forming a low pressure flashing chamber at the outlet of said initial heating chamber, an inlet for steam, means in said shell forming a confined mixing passage for receiving water from said flashing chamber and steam from said initial inlet and thoroughly mixing the steam and water during their flow through the passage, said passage discharging into the shell in a low pressure space exteriorly of said mixing passage to provide a second flashing of the water and final deaeration thereof, means for directing non-condensed steam and released gases from the point of final deaeration into said initial heating chamber, and an outlet for non-condensed steam and released gases opening into said initial flash chamber.

5. Water heating and deaerating apparatus comprising in combination, a shell, means in the shell forming an initial heating chamber, means for passing water in a finely divided form into said chamber, a water seal at the outlet of said chamber, means in said shell forming a low pressure flashing chamber at the outlet of said initial heating chamber, an inlet for steam, means in said shell forming a confined mixing passage for receiving water from said flashing chamber and steam from said initial inlet, thoroughly mixing the steam and water during their flow through said passage, said passage discharging into the shell in a low pressure space exteriorly of said mixing passage to provide a second flashing of the water and final deaeration thereof, the means forming said mixing passage being arranged to form a passage of gradually increasing cross-

sectional area from its entrance end to its discharge end.

6. Water heating and deaerating apparatus comprising in combination, a shell, means in the shell forming an initial heating chamber, means for passing water in a finely divided form into said chamber, a water seal at the outlet of said chamber, means in said shell forming a low pressure flashing chamber at the outlet of said initial heating chamber, an inlet for steam, means in said shell forming a confined mixing passage for receiving water from said flashing chamber and steam from said initial inlet and thoroughly mixing the steam and water during their flow through said passage, said passage discharging into the shell in a low pressure space exteriorly of said mixing passage to provide a second flashing of the water and final deaeration thereof, the means forming said mixing passage being arranged to form a passage of gradually increasing cross-sectional area from its entrance end to its discharge end, and means for directing the steam and water into said mixing passage in substantially parallel flow directions.

7. Water heating and deaerating apparatus comprising in combination, a shell, means in the shell forming an initial heating chamber, means for passing water in a finely divided form into said chamber, a water seal at the outlet of said chamber, means in said shell forming a low pressure flashing chamber at the outlet of said initial heating chamber, an inlet for steam, means in said shell forming a confined mixing passage for receiving water from said flashing chamber and steam from said initial inlet and thoroughly mixing the steam and water during their flow through said passage, said passage discharging into the shell in a low pressure space exteriorly of said mixing passage to provide a second flashing of the water and final deaeration thereof, the means forming said mixing passage being arranged to form a passage of gradually increasing cross-sectional area from its entrance end to its discharge end, and an outlet for non-condensed steam and released gases opening into said initial flashing chamber.

8. In a water heating and deaerating apparatus, an initial treatment chamber, means for introducing water into said initial treatment chamber, a first low pressure flashing chamber receiving partially treated water from said initial treatment chamber, steam introducing means, a second low pressure flashing chamber, means forming a confined mixing passage for receiving water from said first low pressure flashing chamber and steam from said steam introducing means and thoroughly mixing the steam and water during their flow through the passage, said passage discharging the mixed steam and water into said second flashing chamber.

9. In a water heating and deaerating apparatus, an initial treatment chamber, means for introducing water into said initial treatment chamber, a first low pressure flashing chamber receiving partially treated water from said initial treatment chamber, steam introducing means, a second low pressure flashing chamber, means forming a confined mixing passage for receiving water from said first low pressure flashing chamber and steam from said steam introducing means and thoroughly mixing the steam and water during their flow through the passage, said passage discharging the mixed steam and water into said second flashing chamber, and outlet means for non-condensed vapor and

released non-condensable gases opening into said first low pressure flashing chamber.

10. In a water heating and deaerating apparatus, an initial treatment chamber, means for introducing water into said initial treatment chamber, a first low pressure flashing chamber receiving partially treated water from said initial treatment chamber, steam introducing means, a second low pressure flashing chamber, means forming a confined mixing passage for receiving water from said first low pressure flashing chamber and steam from said steam introducing means and thoroughly mixing the steam and water during their flow through the passage, said passage discharging the mixed steam and water into said second flashing chamber, said steam introducing means passing through said first low pressure flashing chamber and constructed and arranged to maintain the incoming steam and the water in said first low pressure flashing chamber in separated heat exchange relationship, and outlet means for non-condensed vapor and released non-condensable gases opening into said first low pressure flashing chamber.

11. In a water heating and deaerating apparatus, an initial treatment chamber, means for introducing water into said initial treatment chamber, a first low pressure flashing chamber receiving partially treated water from said initial treatment chamber, steam introducing means, a second low pressure flashing chamber, means forming a confined mixing passage for receiving water from said first low pressure flashing chamber and steam from said steam introducing means and thoroughly mixing the steam and water during their flow through the passage, said passage discharging the mixed steam and water into said second flashing chamber, and pressure actuated means for preventing backflow into said steam introducing means upon lowering of the pressure of the incoming steam below a predetermined degree.

12. In a water heating and deaerating apparatus, an initial treatment chamber, means for introducing water into said initial treatment chamber, a first low pressure flashing chamber receiving partially treated water from said initial treatment chamber, steam introducing means, a second low pressure flashing chamber, means forming a confined mixing passage for receiving water from said first low pressure flashing chamber and steam from said steam introducing means and thoroughly mixing the steam and water during their flow through the passage, said passage discharging the mixed steam and water into said second flashing chamber, and means for directing non-condensed steam and released non-condensable gases from said second low pressure flashing chamber into said initial treatment chamber.

13. In a water heating and deaerating apparatus, an initial treatment chamber, means for introducing water into said initial treatment chamber, a first low pressure flashing chamber receiving partially treated water from said initial treatment chamber, steam introducing means, a second low pressure flashing chamber, means forming a confined mixing passage for receiving water from said first low pressure flashing chamber and steam from said steam introducing means and thoroughly mixing the steam and water during their flow through the passage, said passage discharging the mixed steam and water into said second flashing chamber, means for directing non-condensed steam and released non-con-

densible gases from said second low pressure flashing chamber into said initial treatment chamber, and outlet means for non-condensed vapor and released non-condensable gases opening into said first low pressure flashing chamber.

14. In a water heating and deaerating apparatus, an initial treatment chamber, means for introducing water into said initial treatment chamber, a first low pressure flashing chamber receiving partially treated water from said initial treatment chamber, steam introducing means, a second low pressure flashing chamber, means forming a confined mixing passage for receiving water from said first low pressure flashing chamber and steam from said steam introducing means

and thoroughly mixing the steam and water during their flow through the passage, said passage discharging the mixed steam and water into said second flashing chamber, said steam introducing means passing through said first low pressure flashing chamber and constructed and arranged to maintain the incoming steam and the water in said first low pressure flashing chamber in separated heat exchange relationship, and a flange on the outlet end of said steam introducing means for directing the steam and water into said mixing passage in substantially parallel flow directions.

JOSEPH F. SEBALD.
